ATTORNEY

UNITED STATES PATENT OFFICE.

ANTON A. LIBERA, OF THORNDIKE, MASSACHUSETTS.

RAIN SIGNAL.

Application filed July 2, 1920. Serial No. 393,701.

To all whom it may concern:

Be it known that ANTON A. LIBERA, a citizen of the United States of America, residing at Thorndike, in the county of Hampden and State of Massachusetts, has invented 5 certain new and useful Improvements in Rain Signals, of which the following is a specification.

This invention relates to improvements in 10 rain signals and its leading object is to provide a rain signal including an audible alarm and a breakable strip normally retained under tension to hold the alarm inoperative and adapted to be weakened by the deposit of 15 rain thereon, to permit of the operation of the alarm at the time of the fall of the rain.

Another object of the invention is to provide improved means for holding the breakable strip under tension and means co-operating therewith to release the alarm mechanism when the strip is broken.

Another object of the invention is to provide a support capable of adjustably holding the device in various angular and spaced 25 relations to a window sill.

With the above and other objects in view the invention relates to new and useful improvements, combinations, and arrangement of parts clearly described in the following 30 specification and fully illustrated in the accompanying drawings, in which:

Figure 1 is a side elevation.

Figure 2 is an end view.

Figure 3 is a top plan view.

Figure 4 is a longitudinal sectional view.

Figure 5 is a detailed view showing the automatic trip for releasing the signal retaining lever.

Referring to the accompanying drawings 5 40 designates a case comprising a housing 6 for the signal and the actuating mechanism therefor and a housing 7 adapted to contain a roll of breakable paper or the like and means for limiting the unrolling of the 45 paper whereby the paper can be maintained under tension, the housing 6 being connected to the housing 7 by means of downwardly offset bridge piece or connection 8.

In the housing 7 a supply roll 9 is mounted 50 upon a shaft 10 which is journalled on the sides of the case 5 and carries on one end a crank 11. The roll 9 is engaged by a brake shoe or the like 12 which is carried by the arms 13 and 14 pivotally mounted upon the 55 shaft 15 journalled on the sides of the housing 7. The shoe 12 is held under tension

against the roll 9 by means of a spring 16 mounted upon the shaft 15 and arranged to maintain tension against the arms 13 and 14. The shoe 12 is disengaged from the roll 60 9 by means of a lever 17 pivotally connected at 18 to said shoe and provided with a pin 19 having sliding connection in a slot 20 of the arm 21 fixed to the shelf 22 of the housing 7.

The web or strip 23 from the roll 9 is extended across the connecting or bridge piece 8 and is gripped between the lower jaw 24 and the upper jaw 25 of a clamp carried by the spring propelled slide 26. The upper jaw 70 25 is mounted upon the side bars 27 pivotally supported by the shaft 28 carried by the sliding base 26. The shaft 28 carries a spiral spring which maintains tension against a lever 29 having connection at one end with the upper jaw 25 and a fulcrum upon the bar 30 connected with the side bars 27. By depressing the terminal 29^a the upper jaw 25 may be elevated above the lower jaw 24 and the web 23 secured there between.

The base 26 is mounted to slide on horizontal guides 31 provided on opposite sides of the housing 6 and is propelled by means of a spring 32 which is secured at one end at 33 and at the other end engaging a lever 34 which is pivoted at 35 to the housing 6 and is pivotally connected with the link 36 which link is pivotally connected with the upright lever 37 at 38 and the lever 37 is pivotally connected at 39 with a lug 40 provided on the under side of the sliding base 26.

In the housing 6 a clock spring mechanism of any suitable type is arranged, the main shaft 41 of which extends through the sides of the housing and is adapted to carry the winding key 42. The clock spring mechanism is adapted to operate a vibrating hammer 43 which is adapted to strike against the bells or gongs or audible sounding means 44 supported upon the upright posts 45 carried 100 by the shelf 46 arranged within the housing 6. The mechanism by which a hammer 43 is vibrated may be of any desired type, such as that as is used in alarm clock constructions.

The vibrating hammer 43 is mounted upon 105 a shaft which is equipped with the usual stop arm 47 and this stop arm is adapted to be engaged by a pin 48 carried by a lever 49 pivotally supported upon the shaft 50 which shaft is supported at its ends on the housing 110 6. An abutment plate 51 is connected to the lower end of the lever 49 and a lever 52 is

pivotedly connected at 53 with the lower end of the lever 49 and extends upwardly and has connection at 54 with the lever 55 which is pivoted at 56 to the shelf 45 by means of 5 a lug or the like 57 carried by said shelf. The lever 55 carries a weight 58 on one end thereof and is provided with a slot 59 in which the upper end of the lever 49 works and also with the slot 60 in which the guide 10 pin 61 projects, said guide pin being secured to the shelf 46. The weight 58 is adapted to hold the plate 51 in position to be engaged by the striker arm or projection 62 carried by the sliding base 26, so that when the exposed portion of the web 23 is weakened by 15 the fall of rain water thereon and said web breaks under the tension maintained by the spring 32 the arm 62 will strike against the abutment plate 51 and the lever 49 will be moved away from the stop arm 47 so as to 20 disengage the stop pin 48 from said arm 47 and the hammer 43 will be released to vibrate under the automatic action of the alarm spring mechanism contained in the 25 housing 6. When it is desired to lock the hammer 43 against movement the shaft 63 which carries the crank arm 64 may be rotated so that the crank arm 64 will engage the hammer 43 and prevent vibratory movement 30 thereof.

It will be seen that when the web 23 is maintained under tension by the propelling spring 32 and said paper web or the like is weakened by rain water so that the tension 35 of the spring 32 will break said web the striker arm 62 will be propelled by the action of the spring 32 so as to abut against the plate 51 and disengage the stop pin 48 from the arm 47 so that the hammer will be 40 released to vibrate under the action of the spring mechanism until manually stopped by operating the shaft 63 by means of its crank 63^a.

The mechanism contained in the housing 45 6 is protected by means of a swinging cover 65 and the mechanism contained in the housing 7 is protected by a swinging cover 66.

The case 5 is provided with depending 50 brackets 67 which are pivotally secured to the upstanding brackets 68 carried by the frame 69. The frame 69 comprises parallel

spaced plates each of which is formed with a slot 70, the two slots being disposed in alignment. Between the plates 69 the head 71 of a clamp member 72 is adapted to slide, 55 said head being formed with outwardly projecting lugs 73 which slidably extend through the slot 70. The clamp member 72 carries a clamping screw 74 which is adapted to engage the shank 75 of the clamp member 76, which is equipped with a screw 77. The device is clamped between the head 77^a of the bracket screw 77 and the jaw of the member 74, as shown in Figure 1. In this relation the frame 69 may be slidably 60 shifted upon the lugs 73 or the case 6 adjusted to various angular relations by reason of the pivotal connection between the bracket 67 and 68. This angular adjustment may be varied at will by means of the 65 screws 78 and 79 which are pivotally secured at their ends to the brackets 80 and 81 carried by the case 5 and the frame 69 respectively. The confronting ends of the screws 78 and 79 are provided with right and left 70 screw threads and are engaged by the turnbuckle 82, the manipulation of which will 75 adjust the case 5 at various angular relations upon the brackets 67 and 68.

Having described my invention I claim:

1. A rain signal comprising a case having a roll therein, an absorbent rupturable strip on the roller and extendable therefrom, means for retarding the rotation of the roll, means for holding said strip under tension 85 slidably on said case, and a signal adapted to be actuated by said means on the rupture of said strip.

2. A rain signal comprising a case, an audible signal therein, a member slidable on the case and having means to actuate the signal, said member being provided with a gripper means for holding said member under tension, a fabric strip adapted to be clamped by said gripper, a roll for said strip, 90 and a tension device for said roll, said case being provided with a gap across the said strip to receive rain drops.

Signed by me at Palmer, Hampden County, Massachusetts.

ANTON A. LIBERA.
